(57) CLAIM

The ornamental design for a pill box as shown and described.

DESCRIPTION

FIG. 1 is a top perspective view of a pill box, showing my new design;

FIG. 2 is a bottom perspective view thereof;

FIG. 3 is a front elevational view thereof, the rear elevational view being a mirror image of FIG. 3;

FIG. 4 is a left side view thereof, the right side view being a mirror image of FIG. 4;

FIG. 5 is a top plan view thereof;

FIG. 6 is a bottom plan view thereof; and,

FIG. 7 is a top perspective view of the pill box in a detached state.

The broken lines in the figures are for the purposes of illustrating portions of the pill box, which form no part of the claimed design.
